SAFETY RAZOR

John Francis O'Malley, Flushing, N. Y.

Application August 5, 1936, Serial No. 94,405

1 Claim. (Cl. 30—68)

This invention relates to safety razors, an object of the invention being to provide a safety razor having an improved construction and arrangement of guard and cap constituting clamping means for a double edged safety razor blade between them, said parts being capable of adjustment so as to accommodate various thicknesses of blade and permit flexing of a thin blade and securely clamping a rigid blade without flexing the same.

Another object is to provide an improved construction of guard and cap which insures a proper positioning of the blade and the retention of said blade in proper position under all conditions.

A further object is to provide a safety razor of this character which can be readily taken apart, thoroughly cleaned and reassembled.

With these and other objects in view, the invention consists in certain novel features of construction and combinations and arrangements of parts, all of which will be more fully hereinafter described and pointed out in the claim.

In the accompanying drawing—

Figure 1 is a view in side elevation of my improved safety razor with the parts assembled for use;

Fig. 2 is a view in transverse section through the center of the head of the razor and a portion of the handle, the rest of the handle being shown in elevation;

Fig. 3 is a top plan view of the razor shown in Fig. 1;

Fig. 4 is a view in longitudinal section through the center of the head of the razor;

Fig. 5 is a perspective view of the razor cap; Fig. 6 is a plan view of the blade;

Fig. 7 is a perspective view of the guard;

Fig. 8 is a view similar to Fig. 2 showing the position of the cap and guard with a rigid or non-flexible blade clamped between them.

My improved safety razor comprises three main parts, namely, a guard 1, a cap 2, and a handle 3. 4 represents a double edged safety razor blade clamped between the cap 2 and guard 1, and said cap is formed centrally with a screw-threaded stud 5 which projects through openings 6 in the blade 4 and through an opening 7 in the guard 1 and engages internal screw threads 8 in the tubular handle 3 so that when the handle is screwed tightly against the guard the cap 2 will be drawn downward to securely clamp the blade 4 between the cap and the guard. While I employ the terms cap and guard to indicate the parts of the razor head such as

commonly employed in the art, it is to be noted that as a matter of fact both the members 1 and 2 constitute guards as they are provided along their longitudinal edges with teeth 9.

The guard 1 is formed on its upper face at both ends with a pair of spaced lugs 10, and extending from these lugs to the side edges of the guard are transversely extending webs 11, and between the lugs 10 at the extreme ends of the guard, recesses 12 are formed in the guard. The cap 2 is provided in its ends with spaced recesses 13 to receive the lugs 10, and between these recesses 13 longitudinally extending bars 14 are provided which extend beyond the ends of the cap and at their extremities are provided with downwardly extending fingers 15 which are adapted to be positioned in the recesses 12 in the guard. The blade 4 is of the double edged type and is provided in its ends with spaced recesses 16 which receive the lugs 10 of the guard, and the blade is of such a length that it fits nicely between the webs 11 at the ends of the guard. In other words, the blade is confined and held against lateral or longitudinal movement relative to the guard and cap by reason of the fact that the lugs 10 project through the recesses 16 of the blade and the webs 11 confine the ends of the blade and, furthermore, when the cap is screwed down tightly upon the blade its bars 14 and fingers 15 resting in the recesses 12 further confine the ends of the blade so that the blade is incapable of displacement from its normal proper position relative to the guard and cap when the parts are properly assembled.

The blade 4 must of course have a central opening 6, as above defined, to receive the stud 5 of the guard, and where the blade is a flexible one in addition to this opening 6, longitudinal slots 17 are formed centrally of the blade and merging into the opening 6. It is to be understood, as above stated, that my improved razor is adapted to clamp not only a flexible type of blade, which is given an arched flexed formation between the cap and guard as shown most clearly in Fig. 2 of the drawing, but it is also within the scope of the invention to provide a rigid or non-flexing blade which is also securely clamped between the cap and guard as shown in Fig. 8 of the drawing.

While I have illustrated and described what I believe to be the preferred embodiment of my invention, it is obvious that various slight changes may be made with regard to the form and arrangement of parts without departing from my

invention, and hence I do not limit myself to the precise details set forth but consider myself at liberty to make such changes and alterations as fairly fall within the spirit and scope of the claim.

5 I claim:

A razor head including a cap and a guard adapted to clamp a blade between them, spaced lugs integral with the guard at the central portions of both ends thereof, webs extending from 10 the lugs to the sides of the guard, the surface between the lugs being flush with the surface

of the guard, the blade and the cap both having recesses in their ends to receive the webs, integral bars at the ends of the cap between the recesses therein, said bars extending beyond the ends of the cap and adapted to rest between 5 the lugs on the guard, fingers at the ends of the bars adapted to overlie the ends of the blade between the cap and guard, said guard having recesses in its ends receiving the fingers.

10

JOHN FRANCIS O'MALLEY.
